STAGE DISPLAY DEVICE

Filed March 19, 1928

Inventor
Henry Ziemmerman,
By Kent W. Womull atty.

UNITED STATES PATENT OFFICE

HENRY ZIEMMERMAN, OF CHICAGO, ILLINOIS, ASSIGNOR TO CHICAGO CARDBOARD COMPANY, OF CHICAGO, ILLINOIS

STAGE DISPLAY DEVICE

Application filed March 19, 1928. Serial No. 262,872.

This invention relates in general to an advertising display device in the form of a miniature stage and has more particular reference to the construction and the folding or collapsing of the device into a compact easily foldable construction.

An important object of the invention is in the provision of a display device which is easily folded and unfolded. A further important object of the invention is in the provision of means for holding the stage in extended or display condition.

A still further object is in the provision of a removable top which is easily applied and removed and is for the purpose of further strengthening the display device in its extended condition, and is also for the purpose of protecting the contents of the device from dirt and from undesirable lighting effects.

Other objects of the invention will appear hereinafter, the drawings illustrating a preferred embodiment of the invention.

In the drawings;

25 Figure 1 is a perspective of a stage display constructed in accordance with the principles of this invention;

Figure 2 is a vertical section taken on the line 2—2 of Figure 3;

30 Figure 3 is a horizontal section taken on the line 3—3 of Figure 2;

Figure 4 is a sectional view of the device in partially folded condition;

Figure 5 is a top view of the device in collapsed condition; and

Figure 6 is a perspective of a removable top.

In a folding display device of this kind, it is desirable not only that the structure resembles as nearly as possible a complete stage setting, but also that it be foldable with a minimum number of folds into as compact a parcel as possible, considering the size of the device. It is further desirable in folding devices of this kind to insure that they will fold without question in a certain invariable manner, to enable them to be set up and collapsed with the greatest ease by an inexperienced person.

50 It is furthermore desirable that the outer

or face plate be folded upon as few lines as possible and in a direction to place the outer or display faces together so that this outer face will not be broken by a score line when the device is set up or unfolded. Display devices of this kind are usually made of cardboard, and the fold lines are formed by scoring one surface of the material so that the cardboard will easily fold without breaking in the opposite direction. If the scoring is properly done, such devices may be folded and unfolded a number of times without breaking through the material upon the score lines.

Referring now more particularly to the drawings, a face plate 8 has a substantially central score line 9 in its rear face, adapting the front or display side to fold together, as indicated in Figure 4. The central portion of the face plate 8 is provided with a score line 10 and a cut line 11 to form an arch-like opening, the material of which is bent rearwardly upon the score line 10 to form a floor 12 of the stage. The edges 13 of this floor may be bent downwardly to form a stiffening for the edges of the stage.

Secured to the rear of the face plate 8 along the sides only thereof is a back member 14 having score lines 15 and 16 at the rear corners of the stage and having a score line 17 in the opposite face of one of the sides of the back member.

In the rear portion of the back 14 below the level of the floor 12 of the stage a supporting wing 18 is cut out which is bendable forwardly to extend below the floor 12 of the stage and to support it approximately at the rear central portion thereof. At the top of the rear member 14 are side projections 19 and corner projections 20. A separate top member 21 slightly larger in size than the extended rear member 14 is provided with side slots 22 and rear corner slots 23 conforming to the projections 19 and 20 at the top of the rear member so that the projections will enter the slots when the top is pressed down, thereby holding the rear member 14 in distended position, strengthening the stage structure when it is unfolded, and protecting the interior of the stage from dust and dirt and also from

the entrance of light through the top of the stage which may be undesirable for some displays. The forward edge 24 of the top may be turned upwardly, resting against the 5 rear face of the front plate 8 in its distended position and holding it against collapsing movement. It is not intended that the top be secured to the face plate as it is separately applied after the display device is set up and 10 is included as a separate piece. The stage does not absolutely require a top, but maintains its set up position and is more rigid when the top is applied.

To collapse or fold the structure from its 15 set up position, the top 21 is first removed, the floor 12 is raised in alignment with the remainder of the face plate. The central portion of the face plate 8 is bent rearwardly upon the score line 9 which causes the rear 20 member 14 to partially collapse about the score line 17 in one side thereof, as shown in Figure 4, the continuation of this folding movement bringing one side of the face plate 8 against the opposite unscored side of the rear 25 member 14, the scored side of the rear portion of the member 14 on the outside of the face plate, thus substantially enclosing the face plate 8 and folding it with the outer exposed portions together, as clearly indicated 30 in Figure 5.

It is thus evident that the stage will fold compactly and flatly, occupying a minimum space for packing and shipping, the top 21 being no larger in extent than the collapsed 35 device.

In unfolding the device, the above described action is reversed, the mere opening 40 of the folded structure, as shown in Figure 5, correctly extending the parts into their proper relative position, requiring only the downward movement of the floor 12 to hold the front sections in alignment and to properly distend the rear member 14. The side braces 45 13 may be of such a size and shape to require folding before the floor 12 can be placed in its proper position. The application of the top 21, as before explained, further braces and holds the parts in their proper relative positions.

10 I claim:

1. A foldable miniature stage display comprising a front member with a central rear score line adapting the front sides to fold forwardly face to face, a rear member attached at its ends to the sides of the front and having vertical fold lines to form two sides and a back for the stage, one only of the sides being scored vertically to fold inwardly upon itself so that the outer portions thereof are face to face in their folded relation, the other side and the back portion of the rear member being of sufficient length to extend around the scored end of the front member when the structure is folded and having a fold line in alignment with the central

fold line of the front member, thereby substantially enclosing the front member and protecting it in its compact folded form.

2. A miniature stage display comprising a front member with a stage opening having a single vertical fold line adjacent the center adapting the portions thereof to fold face to face, and a rear member attached at its ends to the sides of the front member beyond the edges of the stage opening and extensible at the rear of the front member to form sides and the rear of the stage, the rear member having fold lines at the junction of the sides and rear and a single fold line in one side only whereby this side collapses upon itself in folding, the other side and the back having a fold line therebetween aligning with and extending beyond the central portion of the front member when it is folded.

HENRY ZIEMMERMAN.
